ROTARY PRINTING PRESS

Hans J. Luehrs, Westerly, R. I., assignor to C. B. Cottrell & Sons Company, Westerly, R. I., a corporation of Delaware

Application April 3, 1935, Serial No. 14,385

6 Claims. (Cl. 101—247)

The object of my invention is to provide novel and effective means for raising and lowering the impression roll and for automatically controlling its printing pressure on the design cylinder.

5 My invention includes, generally, a design cylinder, an impression roll, means for raising and lowering the impression roll, and means for automatically controlling the printing pressure between the design cylinder and impression roll.

10 My invention more specifically includes motor means for raising and lowering the impression roll and means for automatically stopping the motor when the printing pressure between the design cylinder and impression roll has reached 15 a predetermined point.

My invention still more specifically includes an impression roll mounted in a main head sliding in the main frame, a back-up roll carried 20 by an auxiliary head having a limited sliding movement in the main head, and means acting through the auxiliary head and its back-up roll for bringing the impression roll into coaction with the design cylinder with a predetermined printing pressure.

25 A practical embodiment of my invention is represented in the accompanying drawings, in which

Fig. 1 represents so much of a rotary intaglio web printing press in side elevation as includes 30 my invention;

Fig. 2 represents a transverse vertical section taken in the plane of the line II—II of Fig. 1, looking in the direction of the arrows;

35 Fig. 3 represents a detail longitudinal vertical section taken in the plane of the line III—III of Fig. 2, looking in the direction of the arrows;

Fig. 4 represents a detail horizontal section taken in the plane of the line IV—IV of Fig. 3, looking in the direction of the arrows;

40 Fig. 5 represents a detail section similar to Fig. 3 with the parts in the positions they assume when pressure has been removed from the impression roll 6;

Fig. 6 represents a detail horizontal section 45 taken in the plane of the line VI—VI of Fig. 1, looking in the direction of the arrows; and

Fig. 7 represents the wiring diagram of the operating control for the motor.

The side frames of the printing press are 50 noted by 1, in which side frames the shaft 2 of the design cylinder 3 is rotatably mounted.

The main sliding head 4 is slidably mounted in the side frames 1 and it is guided therein by the gibs 4*, in which head the shaft 5 of the impression roll 6 is mounted. The shafts 7 and

8 of the web guide rolls 9 and 10 are also rotatably mounted in the main sliding head 4 so as to move with the impression roll 6 toward and away from the design cylinder 3.

5 The auxiliary sliding head 11 is slidably mounted for a limited movement in the main sliding head 4, in which auxiliary sliding head the shaft 12 of a back-up roll 13 is rotatably mounted. The sliding movement of the auxiliary head within the main head is limited, as, for instance, by the adjusting screws 14 carried by the main sliding head 4. Non-rotatable screw-threaded impression screws 15 extend upwardly from the auxiliary sliding head by means of which impression screws the auxiliary head 11 and the main head 4 are raised and lowered with a lost motion connection between the auxiliary and main heads; said heads being guided in their respective side frames by means of the gibs 4*.

10 The means which I have shown for raising and lowering the non-rotatable impression screws 15 to thereby raise and lower the impression and back-up rolls, is as follows:

15 Wide faced helical gears 16 are threaded upon the impression screws 15, which gears are located 20 normally in the bottoms of vertical chambers 17 in the side frames 1. Sliding collars 18 surround the impression screws 15 within the chambers 17 above the wide faced helical gears 16. Between these collars 18 and screw-threaded caps 19, 25 which close the upper ends of these chambers 17, there are interposed coil springs 20 surrounding the said impression screws 15. These screw-threaded caps 19 serve to adjust the tension of 30 these coil springs 20.

35 A divided cross shaft 21, 22 is mounted in the side frames 1, which cross shaft is provided with worm gears 23 meshing with the impression screw helical gears 16. A manually releasable clutch 24 serves to removably lock the cross shaft members 21 and 22 together. These cross shaft members are provided with hand wheels 25 and 26 respectively, for manual operation of the divided cross shaft from either side of the machine or for the independent manual operation of the cross shaft members when unlocked 40 from each other.

45 A reversing electric motor 27 is mounted on a platform 28 carried by one of the side frames 1. The motor shaft 29 carries a pulley 30 which drives a belt 31 passing around a pulley 32 locked by a shear pin 33 to a collar 34 fast on the cross shaft member 22. A limit switch 35 is located 50 in position to automatically operate to shut off the current from the motor 27 when the desired 55

printing pressure is obtained between the impression and design cylinders by the upward movement of the impression screw gears and sliding collars 18, and consequent compression 5 of the coil springs 20. To accomplish this result one of the spring pressed sliding collars 18 is connected through a key 36, a bracket 37 and a link 38 with one arm 39 of a rock lever pivoted at 40 on one of the side frames 1, the other arm 10 of which rock lever is developed into a pointer 41. The lever arm 39 has a cam projection 42 which is located in position to engage and throw the switch 35 to cut off the current from the motor 27 when the printing pressure reaches a 15 predetermined point. Another limit switch 43 is arranged in position to be engaged by a cam 44 carried by the main sliding head 4 to cut off the current from the motor 27 when the limit of upward movement of the main and auxiliary 20 heads, with their rolls, has been reached.

The manually operated electric control for the reversing motor 27 includes the following elements:

A switch 45 is provided for running the motor 25 in a direction to lower the main and auxiliary heads with their rolls. A switch 46 is provided for running the motor in the opposite direction to raise the main and auxiliary heads with their rolls. A third switch 47 is provided for stopping 30 the motor at any time. A relay 48 and contact switch 49 is controlled by the switch 45 and the switch 47. A relay 50 and contact switch 51 is controlled by the switch 46 and the switch 47. These parts and their circuits are of well known 35 and approved construction and will not be more specifically described herein.

In operation: Let it be assumed that the down switch 45 has been closed to cause the motor 27 to rotate the helical gears 16 on the impression 40 screws 15 by means of the worm gears 23 on the divided cross shaft 21, 22, to lower the main and auxiliary heads 4 and 11 respectively, and their rolls from the position shown in dotted lines in Fig. 1. After the impression roll 6 has been 45 brought into contact with the design cylinder 3 and the back-up roll 13 has been brought into contact with the impression roll 6 the further rotation of the helical gears 16 will cause them and the collars 18 to move bodily upward on the impression screws 15 within the chamber 17. This upward movement of the helical gears 16 and collars 18 will compress the coil springs 20 and thereby add pressure through the back-up roll 13 to the impression roll 6 to obtain the 50 desired printing pressure between the impression roll and design cylinder. When the desired printing pressure has been obtained the limit switch 35 is opened by the cam 42 thus automatically shutting the current off from the motor 27.

60 When it is desired to raise the main and auxiliary heads with their rolls the switch 46 is closed to start the motor in the reverse direction, the first effect being to cause the helical gears 16 and their collars 18 to travel downwardly on the impression screws 15 and release the extra tension 65 on the coil spring 20. The next effect will be to cause the upward movement of the impression screws 15 and thereby the preliminary limited upward movement of the auxiliary head 70 with its back-up roll 13. The next effect will be to combine upward movements of the main and auxiliary heads with their rolls.

When the main and auxiliary heads, with their rolls, reach the limits of their upward movement 75 the limit switch 43 is opened by the cam 44, thus

cutting the current off from the motor 27. It will be understood that the motor may be stopped at any time by the switch 47.

It will be noted that the operative connection between one of the spring pressed collars 18 and the arm 39 of the rock lever pivoted at 40 is such as to cause a very quick operation of the switch 35 when the printing pressure of the impression roll reaches a predetermined point.

It will also be noted that the "hand" of the wide faced helical gears 16 is selected with respect to the direction of rotation of the driving worm gears 23 to cause the threads of the helical gears to "run away from" the threads of the worm gears when the helical gears are started on their upward movement against the pressure of the springs 20 as the impression roll comes in contact with its design cylinder. This will reduce the peripheral velocity of the helical gears proportionately to said upward motion at the time when an additional load is imposed upon the worm gears due to the increasing pressure of the said springs 20. This reduced ratio of the worm drive while the wide faced helical gears 16 are moving upwardly is a distinct advantage in the operation of the mechanism.

It is evident that various changes may be resorted to in the construction, form and arrangement of the several parts without departing from the spirit and scope of my invention, and hence I do not intend to be limited to the particular embodiment herein shown and described, but

What I claim is:

1. In a rotary intaglio printing press, a design cylinder, a main sliding head, an impression roll carried thereby, an auxiliary head having a limited sliding movement in the main head, a back-up roll carried by the auxiliary head, and means for bringing the impression roll into coaction with the design cylinder comprising non-rotatable impression screws carried by the auxiliary head, gears threaded on the impression screws, and a motor driven cross shaft having gears meshing with the impression screw gears.

2. In a rotary intaglio printing press, a design cylinder, a main sliding head, an impression roll carried thereby, an auxiliary head having a limited sliding movement in the main head, and means for bringing the impression roll into coaction with the design cylinder at a predetermined pressure comprising spring pressed non-rotatable impression screws carried by the auxiliary head, gears threaded on the impression screws, and a motor driven cross shaft having gears meshing with the impression screw gears.

3. In a rotary intaglio printing press, a design cylinder, a main sliding head, an impression roll carried thereby, an auxiliary head having a limited sliding movement in the main head, and means for bringing the impression roll into coaction with the design cylinder comprising non-rotatable impression screws carried by the auxiliary head, gears threaded on the impression screws, a divided cross shaft having gears meshing with the impression screw gears, a releasable clutch connecting the cross shaft members, and a motor for driving the cross shaft.

4. In a rotary intaglio printing press, a design cylinder, a main sliding head, an impression roll carried thereby, an auxiliary head having a limited sliding movement in the main head, and means for bringing the impression roll into coaction with the design cylinder comprising non-rotatable impression screws carried by the aux-

iliary head, gears threaded on the impression screws, a divided cross shaft having gears meshing with the impression screw gears, a releasable clutch connecting the cross shaft members, 5 and a motor for driving the cross shaft, said cross shaft being also capable of manual manipulation.

5. In a rotary intaglio printing press, a design cylinder, a main sliding head, an impression roll carried thereby, an auxiliary head having a limited sliding movement in the main head, and means for bringing the impression roll into coaction with the design cylinder comprising non-rotatable impression screws carried by the auxiliary head, wide faced helical gears threaded 10 on the impression screws, springs yieldingly holding the impression screw gears at the limits of their downward movements and a motor driven shaft having worm gears meshing with the impression screw gears, said worm gear drive providing a reduced ratio as the impression screw gears are moved upwardly against the pressure 15 of their springs.

shaft having worm gears meshing with the impression screw gears.

6. In a rotary intaglio printing press, a design cylinder, a main sliding head, an impression roll carried thereby, an auxiliary head having a limited sliding movement in the main head, and means for bringing the impression roll into coaction with the design cylinder comprising non-rotatable impression screws carried by the auxiliary head, wide faced helical gears threaded 5 on the impression screws, springs yieldingly holding the impression screw gears at the limits of their downward movements and a motor driven shaft having worm gears meshing with the impression screw gears, said worm gear drive providing a reduced ratio as the impression screw gears are moved upwardly against the pressure 10 of their springs.

HANS J. LUEHRS.
